UNITED STATES PATENT OFFICE.

EUGENE W. VOGEL, OF OAK PARK, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

PROTECTIVE APPARATUS FOR ELECTRIC CIRCUITS.

1,210,568.

Specification of Letters Patent.

Patented Jan. 2, 1917.

Application filed May 1, 1914. Serial No. 835,668.

To all whom it may concern:

Be it known that I, EUGENE W. VOGEL, a citizen of the United States, residing at Oak Park, in the county of Cook and State of Illinois, have invented certain new and useful Improvements in Protective Apparatus for Electric Circuits, of which the following is a specification.

My invention relates to apparatus for protecting an electric circuit against the destructive effect of high potential charges.

One of the primary objects of the invention is to provide certain novel devices, constructions and combinations of devices for effectively protecting an electric circuit both from static charges, due to lightning, which may be of extremely high potential but of relatively short duration, and charges due to crosses with power circuits the potentials of which are likely to be much lower than that of a static charge but which may be equally destructive in their effects because of their greater duration.

The invention has for further objects to provide protective apparatus for electric circuits which will be inexpensive to manufacture, reliable in its operation, susceptible of being easily repaired when necessary, and compact so that it may be conveniently employed in a signal box or in similar situations.

The invention is illustrated, in certain preferred embodiments, in the accompanying drawings wherein—

Figure 1 is a view, in front elevation, of a lightning arrester constructed in accordance with the principles of the invention; Fig. 2, a sectional view taken on line 2—2 of Fig. 1; Fig. 3, a view similar to Fig. 1 with the lightning arrester unit removed so as to show the construction and arrangement of the parts constituting the air gap device for grounding an overcharge of relatively long duration; Figs. 4 and 5, views, in perspective, of the devices constituting terminal clips for the lightning arrester unit and electrodes for the air gap arrester; Fig. 6, a view, in perspective, of one of the binding post terminal plates; Fig. 7, a similar view 50 of a porous, refractory, non-conducting sep-

tum which is arranged between the electrodes of the air gap arrester; Figs. 8 and 9, views, taken, at right angles to each other, of a vacuum lightning arrester unit which may be used in substitution for the unit 55 shown in Figs. 1 and 2; Fig. 10, a sectional view taken on line 10—10 of Fig. 8, and Fig. 11, a view, in perspective, of one of the connecting strips used for connecting the electrodes or terminals with their leading-in 60 wires in the device shown in the preceding three figures.

Like characters of reference designate like parts in the several figures of the drawings.

Referring first to Figs. 1 to 7 inclusive, 25 designates a base of porcelain or other suitable insulating material formed with screw holes 26 for attachment to a signal box or switch board, and with three recesses 27, 28 and 29, the central recess 29 being separated from the end recesses 27 and 28, except for small gaps 30, by integral partitions 31. 32 designates a binding post to which the line wire 33 is connected, and 34 75 a binding post connected to the ground by a wire 35. Another binding post 36 is provided at the upper end of the base which is connected with the binding post 32 by a wire 37 and may be used for the line wire, 80 if more convenient, in place of the binding post 32. The binding posts 34 and 36 are arranged in the recesses 27, 28, respectively. In the same recesses are two terminal clips 38 (Fig. 5) and 39 (Fig. 4) each formed 85 with a plate 40, which plates are clamped to the base by means of metal blocks 41 on the binding posts 34, 36. The blocks are held in position by nuts 42 on the binding posts. The clips are adapted to support a lightning 90 arrester unit, that is, a protecting device, which functions to ground an overcharge of extremely high potential and short duration such as is produced by lightning. Two types of unit are shown in the drawings, 95 either of which can be used in this connection. One type is shown in Figs. 1 and 2. The other type is shown in Figs. 8 to 11 inclusive. It is well known that arresters capable of functioning to the best advantage to 100

protect a circuit from the destructive effects of static charges due to lightning are ordinarily not capable of long withstanding the effects of a continued current of high potential such as may result from a cross with a high power circuit, for example, a trolley wire. In order to give protection against disturbances of this latter sort I provide an air gap arrester of the horn or arc extinguishing type in parallel with the lightning arrester unit. The air gap arrester is preferably constituted as follows: The terminal clips 38, 39 are formed with projecting strips 43, 44 which extend into the middle recess 29 of the base, the extremity of the strip or electrode 44 being in close proximity to the inner end of the electrode 43, the electrodes diverging upwardly from this point. The divergent relationship between the electrodes causes the arc between the electrodes to be extinguished in accordance with the familiar principle of arresters of the horn type. In order to prevent the electrodes from being welded together at the narrowest place of the air gap, a porous septum 45 made of some nonconducting highly refractory material such as lava, unglazed porcelain, or the like is interposed between the electrodes at this point. The porosity of the septum allows a static charge to pass therethrough from one electrode to the other while preventing the possibility of a short circuit due to the welding of the electrodes or other bridging of the air gap which is likely to occur with lightning arresters of the air gap type because of the narrowness of the gap. This element is preferably formed on its sides with tapered cuts or channels 46 in which the electrodes 43, 44 are received. In this manner the septum is held in position between the electrodes, which have a certain amount of elasticity and the gap between the electrodes at its narrowest point may be made as small as desired without having the septum itself so fragile that it would be likely to break with handling or vibration.

The lightning arrester unit shown in Figs. 1 and 2, that is, the device intended to take care of static charges of momentary duration, consists of a tube 47 of non-conducting material such as fiber, filled with a body 48 of carborundum in granular form, and closed at opposite ends by metal caps 49 preferably provided with spikes 50 which project into the carborundum in the tube so as to provide electrodes or terminals for this type of lightning arrester. I am aware of the fact that carborundum has been used in the form of solid blocks in the construction of lightning arresters. When employed in this form a single lightning discharge, or at most a few discharges, so increases the conductivity of the material that it will

ground the normal service current. I have found that if a body of granular carborundum be used between the electrodes or terminals of a lightning arrester a static charge of high potential will be readily grounded through the arrester, and the normal service current will be prevented from passing therethrough; and while the conductivity of the carborundum is to a certain extent increased by repeated discharges the cell may be restored to its original condition by occasionally tapping or shaking it enough to destroy the cohesion between the granular particles.

The vacuum lightning arrester unit shown in Figs. 8 to 11 inclusive consists preferably of an evacuated tube 51 provided at opposite ends with caps 52 and electrodes or terminals 53 having their adjacent edges serrated which are secured together and held in proper relation with each other by mica strips 54 bound to either side of these members by bolts 55. The electrodes or terminals are suspended in the tube by means of connecting strips 56 having loops 57 engaging loops 58 formed in the ends of the leading-in wires 59 which are sealed through the glass wall of the tube and connected with the caps 52. The mica strips 54 serve to protect the glass wall of the vessel from the effects of the discharges between the electrodes or terminals besides accurately positioning these members with respect to each other.

While I have described my invention in certain preferred embodiments, modifications might be devised without departing from the principles of the invention. Therefore I do not wish to be understood as limiting the invention to the particular constructions, arrangements and devices shown and described except so far as is required by the express language of certain of the claims herein.

I claim:

1. In apparatus of the character described, the combination with a pair of electrodes, one connected with the line to be protected, and the other of which is grounded, of a porous septum of non-conducting, refractory material arranged between said electrodes, for the purpose described.

2. In apparatus of the character described, the combination with a pair of electrodes, one connected with the line to be protected, and the other of which is grounded, of a porous septum of non-conducting, refractory material arranged between said electrodes, said electrodes diverging from the point of separation by the septum so as to extinguish the arc between said electrodes.

3. In apparatus of the character described, the combination with a pair of diverging electrodes, one connected with the line to be

protected and the other grounded, of a porous septum of non-conducting, refractory material arranged between said electrodes and formed with channels on opposite sides in which said electrodes are received.

4. In apparatus of the character described, the combination with a pair of electrodes, one connected with the line to be protected and the other grounded, said electrodes spaced apart in fixed relation to form an air gap between them, of a lightning arrester unit, comprising terminals, one of which is grounded and one of which is connected to said line wire, providing a gap, the resistance of which to a static charge of high potential and short duration is less than the resistance of the aforesaid air gap.

5. In apparatus of the character described, the combination with a pair of electrodes, one of which is connected with the line to be protected, and the other grounded, said electrodes arranged with an air gap between them, of a porous septum of nonconducting, refractory material arranged in said air gap, and a lightning arrester unit, one terminal of which is connected with said line wire and the other grounded, providing a gap, the resistance of which to a static charge of high potential and short duration is less than the resistance of the aforesaid air gap.

6. In apparatus of the character described, the combination with a pair of electrodes, one connected with the line to be protected and the other grounded, said electrodes arranged in diverging relationship with an air gap between them, of a porous septum of non-conducting, refractory material arranged in said air gap, and a lightning arrester unit, one terminal of which is connected with said line wire and the other grounded, providing a gap, the resistance of which to a static charge of high potential and short duration is less than the resistance of the aforesaid air gap.

7. In apparatus of the character described, the combination with a base of refractory, non-conducting material, of a pair of terminal clips on said base, a lightning arrester unit removably mounted in said terminals, each of said terminals being provided with a projecting element, which elements are spaced apart in fixed relation and together constitute an air gap arrester in parallel with said unit, and a porous septum of non-conducting, refractory material arranged between said electrodes.

8. In apparatus of the character described, the combination with a base of refractory, non-conducting material, of a pair of terminal clips on said base, a lightning arrester unit removably mounted in said terminals, each of said terminals being provided with

a projecting element, which elements are spaced apart in fixed divergent relationship with each other so as to form an arc extinguishing air gap, and a porous septum of non-conducting, refractory material arranged in said air gap.

9. In apparatus of the character described, the combination with a base of refractory, non-conducting material formed with a recess, of a pair of terminal clips on said base, and a lightning arrester unit removably mounted in said terminals, each terminal being provided with an electrode which projects into said recess: said electrodes being arranged in divergent relationship with each other so as to form an arc extinguishing air gap.

10. In apparatus of the character described, the combination with a base of refractory, non-conducting material, of a pair of terminal clips on said base, a lightning arrester unit removably mounted in said terminals, each of said terminals being provided with a projecting element, which elements together constitute an air gap arrester in parallel with said unit, said base being formed with insulating partitions extending between each terminal clip and the projecting element of the other clip.

11. In apparatus of the character described, the combination with a base of non-conducting, refractory material formed with three recesses in line with each other, of a pair of terminal clips one in each outer recess, and a lightning arrester unit arranged in said clips, said clips being provided with electrodes which project into the other recess so as to provide an air gap arrester in parallel with said unit.

12. In apparatus of the character described, the combination with a base of non-conducting, refractory material formed with three recesses in line with each other, of a pair of terminal clips one in each outer recess, and a lightning arrester unit arranged in said clips, said clips being provided with electrodes which project into the other recess in divergent relationship with each other so as to provide an arc extinguishing air gap arrester in parallel with said unit.

13. In apparatus of the character described, the combination with a base of non-conducting, refractory material formed with three recesses in line with each other, of a pair of terminal clips one in each outer recess, a lightning arrester unit arranged in said clips, said clips being provided with electrodes which project into the other recess in divergent relationship with each other so as to provide an arc extinguishing air gap arrester in parallel with said unit, and a porous septum of refractory, non-conducting material arranged between said electrodes.

14. A lightning arrester unit consisting of an evacuated vessel having leading-in wires sealed through opposite ends thereof, a pair of electrodes in said vessel, a pair of mica strips secured to opposite sides of said electrodes, and metal connecting strips connected with said electrodes respectively and having loops engaging respectively said leading-in wires.
